CAR SIDE CONSTRUCTION AND LOAD
BRACING APPARATUS

Erwin G. Mangels, Davenport, Iowa

Application September 13, 1947, Serial No. 773,808

5 Claims. (Cl. 105—404)

1

This invention relates to car side constructions and in particular to an improved construction for car sides for railway freight cars such as box cars, cattle cars and the like.

It is an object of the present invention to provide a car side construction having an increased ratio of strength to weight. In other words, it is an object to provide a car side having substantially greater strength if the car is constructed to be of the same weight as conventional cars now in use or if the car is constructed to be of equal strength a car embodying the present invention will be of substantially lighter weight, which, of course, results in a higher pay load capacity.

Another object is to provide apparatus for bracing railway box car loads in which the apparatus is an integral part of the car side construction so that the interior car walls are flush and so that the car, if desired, may be used in a normal manner without interference by the load bracing apparatus.

The present day utility loading or adjustable car bracing mechanisms are objectionable in that they require the use of special bracing members having permanent attachments carried thereby and require that a complete set of bracing members with their special attachments be carried in the car at all times. This apparatus is often very heavy and in some instances adds as much as one-third or more to the weight of the car when empty, thus substantially reducing the pay load that can be carried when the car is so equipped. It is therefore an object of the present invention to provide an apparatus for adjustably bracing the load which does not require carrying a large supply of heavy bracing members. The apparatus of the present invention is constructed so that the fixtures for supporting the bracing members are built into the construction of the car side and it is possible to utilize ordinary bracing members of dunnage lumber available at the point where the car is loaded.

A still further object of the present invention is to provide a simplified and improved form of car side construction employing an exterior sheathing and car side post members in which the side post members are integrally constructed as part of the exterior sheathing panels, thus reducing the amount of fabrication in producing a car and decreasing the weight necessary to obtain adequate strength.

Another object is to provide an improved car side construction utilizing an improved design of side post member which has greater longitudinal

2

extent, thus reducing the width of unsupported sheathing between adjacent posts, resulting in a stiffer car side having a much higher resistance to stresses tending to bulge the car side.

5 Other objects and advantages will become apparent from the following detailed description accompanied by the drawings, in which:

Figure 1 is a fragmentary side elevation of a railway box car embodying the present invention 10 with parts broken away to show how the invention may be applied;

Fig. 2 is a sectional view taken substantially on line 2—2 of Fig. 1;

Fig. 3 is an enlarged fragmentary sectional 15 view taken substantially on line 3—3 of Fig. 1 showing a detail of the car side construction;

Fig. 4 is an enlarged fragmentary sectional view taken substantially on line 4—4 of Fig. 1 20 showing in horizontal section details of the car side construction;

Fig. 5 is an enlarged horizontal sectional view of a modified form of car side construction;

Fig. 6 is a similar enlarged horizontal section 25 at another point on the car side illustrating a modified form of car side construction; and

Fig. 7 is an enlarged fragmentary horizontal sectional view of a portion of a car side to illustrate the application of the present invention to the rebuilding of existing railway freight cars.

30 In the construction of present day railway freight cars such as box cars and the like the car side construction essentially comprises a plurality of spaced side post members to which are secured an exterior sheathing providing an outer 35 surface or wall of the car. Generally there is secured to this assemblage an inner lining covering and concealing the side posts to provide an interior wall in the car. These side posts comprise the framework of the car side and it is necessary that they be relatively stiff members 40 resistant to twisting, bending, in addition to stresses which would tend to bulge the car sides outwardly. In the past, side post members have been formed of angle bars or Z-bars or the like.

45 A preferred form of side post member embodying the present invention is indicated in the drawings by the numeral 1 and may best be seen in Fig. 4. A plurality of these side post members are arranged vertically, extending between and 50 connected to the side plate, indicated by the numeral 2, at the top of the car side construction and the side sill, indicated by the numeral 3, at the bottom of the car side construction. These side post members are arranged at intervals longitudinally along the car sides usually 55

at opposite points from end sill to end sill of the car. To the exterior of these side post members are secured a plurality of sheathing panels 4 which form the exterior wall of the car side. This sheathing may be made of almost any desired material but it is preferable to use metal sheets for ease of assembling by welding and in order to obtain adequate strength from the thinnest material.

In the form of the invention shown in Figs. 1 through 4, each of the side post members 1 is an integral portion of the sheathing panel 4 and disposed along one vertical edge thereof. The opposite vertical edge of each sheathing panel overlaps an adjacent side post member and is secured to said side post member in any suitable manner, such as welding, riveting or the like. It may be seen that the side post members and sheathing form the frame and outer wall of the car side. At the interior of the sheathing, angle bars 5 may be disposed and secured to the sheathing and/or the side posts to hold furring or nailing strips 6 in order that suitable inner lining, indicated by the numeral 7, may be nailed thereto to provide an interior wall of the car side construction. The furring or nailing strips 6 may be secured to the angle bars 5 by a bolt 8 passing through the angle bars and the furring as shown in Fig. 4.

At the location of the door opening in the car side construction the sheathing panel may be constructed without an integral side post member, and in this instance the sheathing panel may be secured directly to a door post 10, as shown in the right hand portion of Fig. 4.

The multiple channel side post members may include at least one and preferably two channel shaped recesses 11 opening toward the exterior of the car side wall and at least one channel shaped recess 12 opening into the interior of the car. While adjacent walls of the recesses 11 and 12 are shown in the drawings as being substantially at right angles to each other, it will be seen that this angle may be varied, if desired.

The side post members 1 have outer faces formed by vertically disposed sheathing engaging flange portions 13, some of which may be edge flanges of the side post member and some of which may be intermediate flange portions of the post members disposed between the connecting adjacent channel shaped recesses. These flange portions 13 afford relatively wide contact areas between the side post members and the exterior sheathing which facilitate a secure engagement between sheathing and side post members by welding, riveting or the like. Further, it may be seen that when the sheathing of an adjacent panel overlaps the side post member and is secured thereto, such sheathing covers the channel shaped recesses 11 and forms with the side post members two closed spaced tubular columns at an edge of each sheathing panel which provide a sturdy and stiff, though light weight, construction. The form of side post member shown in the drawings in cross section has the appearance of two connected U-shaped portions with edge flanges at the free ends of the legs of the U's and an intermediate flange portion in the plane of the edge flanges connecting the U-shaped portions.

At the interior of the car side wall the side post members 1 have flange portions 19 which in the form of side post member shown in the drawings are spaced on each side of the interiorly facing recess 12 and form the bottoms of the outwardly facing recesses 11. These spaced flange

portions 19 provide for increased strength of the car side construction due to the manner in which they are secured to the frame of the car. The side post members 1 may be secured to the floor 5 and sill 3 of the car in any suitable manner. The ends of the side post members 1 abut the underside of the side plate 2 and may be welded or otherwise secured thereto along the longitudinal lines at the junction of the top edges of the flanges 19 and the side plate 2, as indicated by the numeral 9 in Fig. 2. In the form of side post members shown in the drawings this affords connection along spaced longitudinal lines and provides a very secure connection of the side post members to the side plate 2.

Since the side post members are formed of sheet metal stock and are of substantially greater width than previous designs of side post members, fewer posts are required and a stiff car side construction results with relatively few side post members. The wall structure of the present invention has high resistance to stresses tending to bulge the car side walls due to the fact that the width of unsupported sheathing between the wide side post members is reduced.

At suitable vertical intervals along the channel shaped recess 12, stiffening elements 14 may be disposed and secured to the walls of the recess 12. As may be seen in Fig. 3, a preferred form of stiffening element comprises a short channel shaped section of sheet metal disposed transversely of the recess 12 and welded to the side walls of the recess 12. These stiffening elements resist relative movements of the side walls of the recesses and add a great deal of rigidity and stiffness to the side post members. These stiffening elements resist stresses tending to cause relative lateral movements of the recessed side walls are particularly effective in increasing the resistances to stresses tending to bulge the car side walls. The side posts are additionally stiffened by the lining 7 which engages with the outer side walls of the outwardly facing channels of the side posts.

In addition these stiffening elements serve another function in combination with the channel shaped recesses 12 which open to the interior of the car. The recesses 12, which are provided at opposite points along the car side wall, serve as keepers for the ends of transverse bracing members 15, and are extremely helpful in bracing the load placed in the car. The stiffening elements 14 may be used to support such transverse bracing members at spaced car heights.

The ends of the transverse bracing members 15 may be inserted within the recesses 12 by tilting the longitudinal axis of such transverse bracing members until the distance between the ends of the bracing member is shorter than the distance between opposite side post members. The vertical spacing of the stiffening elements is preferably such to permit the insertion of a desired number of transverse bracing members between adjacent stiffening elements.

For example, as shown in Fig. 1 by the use of a plurality of bracing members 15 having their ends disposed in the channel spaced recesses 12, an end of the car may be partitioned to form a bin for carrying small loose articles, as indicated by the numeral 16 in Fig. 1. At the height of one of the stiffening elements 14, transverse bracing members 15 may be used to support a removable floor or deck 17 useful to tier the load. The numeral 18 indicates a crated object carried by the floor or deck 17 and additionally

braced by a transverse bracing member disposed at the bottom of the article on the floor or deck 17 and a second transverse bracing member supported by the next higher stiffening element 14 in the region of the top of the article.

As another illustration of the use of the present car side construction in the bracing of railway car loads, the numeral 20 indicates an object shorter than the space between adjacent recesses 12 and braced by the use of transverse bracing members and a plurality of short longitudinal bracing members 21 supported between the object and the transverse bracing members 15.

It may thus be seen that the present invention in addition to providing a sturdy, rigid car side construction also incorporates an apparatus for bracing the load of the car which may be used to brace a large variety of objects of varying size and shape. Furthermore, the bracing apparatus does not utilize special bracing members with fixed attachments which necessitates their being carried in the car whether used or not. All that is required is a supply of dunnage lumber as is available at loading sites for normal dunnage purposes. In fact, a quantity of the transverse bracing members 15 may be made in advance by cutting timbers to the proper predetermined length for use in freight cars embodying the present invention.

Another important feature accruing from the use of the herein described car side construction is that it overcomes one of the major objections to conventional dunnaging practices. Normally a freight car load is braced by nailing dunnaging lumber to the car lining so that each load is braced by cutting and fitting bracing members to fit as the car is loaded. This appreciably increases loading time and justifies the cost of utility loading apparatus now on the market. Also, in the desire for speed of unloading, the removal of the dunnage lumber is accompanied by damage to the car lining. After a relatively few trips it may be necessary to remove and replace the car lining, which is a substantial maintenance item.

When it is not desired to use the load bracing apparatus afforded by the present invention the car is ready for normal use without removing any equipment or making any alterations because the fixed portions of the load bracing apparatus reside in the channel shaped recesses 12 which are wholly disposed within the car side wall.

Fig. 5 illustrates a modified form of car side embodying the present invention which comprises side post members 23 of the same configuration as shown in Figs. 1 through 4, except that the side post members are not integrally constructed as a part of a sheathing panel. Sheathing panels 24 are provided and may be located so that their adjacent edges overlap in the region of the central flange portion 25 between the two channel shaped members making up the side post 23. Thus, the adjacent overlapped portions of the sheathing panels may be secured together and to the side post member at this point.

In Fig. 6 an alternative form of car side wall construction in the region of the door opening is shown. In this modification side post members 28 are integrally formed along one side edge of the sheathing panel 29, as shown in Figs. 1 through 4 of the drawings. To form a door post in the region of the door opening a side post member 28 is disposed adjacent the desired location of the door opening. A door post construc-

tion is then afforded by providing a sheathing section 30 which overlaps and covers the exterior of the side post member 28 and has a flange 31 extending inwardly to the interior of the car side wall for a distance equal to the thickness of such side wall. A suitable insert 32, shown in the drawing as formed of wood, may be used to provide a nailing strip to which the lining may be secured and to back up flange 31 of the door post construction. The insert or door post nailing strip 32 may be bolted or otherwise suitably fastened to the side post member and the sheathing section 30 as indicated in Fig. 6.

The present invention is also extremely beneficial in the rehabilitation or remodeling of existing railway cars. For example, at the time when a car lining is removed for replacement, side post members embodying the present invention may be built into the car side wall. If the exterior sheathing is in satisfactory condition, it may be left in place and side post members of the type shown in Fig. 5 may be secured thereto. Such a construction would greatly stiffen and strengthen the car side walls and will at the same time provide the improved load bracing apparatus of the present invention.

Fig. 7 illustrates the addition of side post members embodying the present invention to an existing car side construction. The numeral 35 indicates the side post member of the original construction which is of the conventional Z section. The original sheathing panels 36 meet in a lap joint and are secured to the side post 35. With the lining removed it is a relatively simple matter to secure side post members 37 embodying the present invention to the sheathing at opposite points along the car side walls. Suitable nailing strips 38 may be secured to the new side post members 37 in any of the well accepted methods so that a suitable lining indicated by the numeral 39 may be secured to the car side wall construction to provide a flush surface on the interior of the car.

While the above description of the present invention has been in connection with railway box cars, it may be readily seen that the invention may be applied equally beneficially to constructions of other types of cars, such as, for example, a stock car used for carrying cattle, when built with a single floor or for smaller animals such as pigs, sheep or chickens when built with two or more floors or decks. In applying the invention to cars of this type the frame of the car side wall would be similar to that described above. The side post members would be secured at opposite points along the car, extending from the side plate to the side sill. Instead of the sheathing panels applied as the exterior wall of the car, a plurality of spaced horizontal slats may comprise the outer car wall.

It is to be understood that variations and modifications of the specific devices herein shown and described for purposes of illustration, may be made without departing from the spirit of the invention.

What I claim is:

1. Apparatus for bracing the load of a railway car which comprises in combination with the outer car side walls, side post members disposed at opposite points along said car side walls and each defining a vertically extending channel shaped recess opening to the interior of said car, spaced flange portions carried by said side post members for attachment to said outer car wall, and means extending between and secured

to the walls of each of said vertically extending channel shaped recesses to stiffen said side post members and afford a support for transverse load bracing members which extend across the interior of the car from side wall to side wall.

2. Apparatus for bracing the load of a railway car which comprises in combination with outer car side walls, side post members disposed at opposite points along said car side walls and each defining a vertically extending channel shaped recess opening to the interior of said car, spaced flange portions carried by said side post members for attachment to said outer car walls, and means extending between and secured to the walls of each of said vertically extending channel shaped recesses to stiffen said side post members and afford a support for transverse load bracing members which extend across the interior of the car from side wall to side wall, said means being disposed at opposite equal heights in said recesses and including channel shaped members extending transversely between the walls of said recesses.

3. A railway car side construction which comprises a plurality of vertically disposed sheet metal side post members spaced along the car side, said side post members each being formed to provide spaced parallel and vertically extending channels facing toward the exterior of the car side, a channel intermediate said spaced channels facing toward the interior of the car and open toward such interior, the side walls of which are side walls of the spaced channels and an attaching flange at the outer edge of a side wall of an outwardly facing channel, and a plurality of vertically spaced transversely disposed rigid bracing elements extending across the space between the side walls of each inwardly facing channel and attached at their ends to said side walls; said bracing elements affording supports at various heights for transverse load bracing members.

4. A railway car side construction such as defined in claim 3 in which said bracing elements are channel shaped sheet metal members disposed with their channels facing the exterior of

the car side, and having their ends welded to the side walls of the inwardly facing channel of the side post member.

5. A railway car side construction which comprises exterior sheathing panels, a plurality of sheet metal side post members spaced along the car side, said side post members each being formed to provide spaced parallel exteriorly facing channels and a vertically extending channel between the exteriorly facing channels facing toward and opening to the interior of the car side, said post members having spaced flange portions at the outer side thereof engaging said sheathing panels and attached thereto, inner lining panels intermediate said posts, spaced inwardly from the sheathing and bridging the spaces between exteriorly facing channels of the spaced side post members, and vertically spaced stiffening elements in the interiorly facing channels of said side posts; said stiffening elements extending transversely across the space between the side walls of said interiorly facing channels and being secured at their ends to the channel side walls, said bracing elements affording supports at various heights for transverse load bracing members.
